UNITED STATES PATENT OFFICE.

CLAUDE WEYANDT, OF CLAYSBURG, PENNSYLVANIA.

RADIATOR CAP.

Application filed October 20, 1925. Serial No. 63,649.

This invention relates to new and useful improvements in motor vehicle radiator caps, and has for its primary object to provide such a device that will enable the radiators to be filled without the necessity of unscrewing or otherwise entirely removing the cap from the filling neck of the radiator.

A further and important object of the invention is to provide means for facilitating the accurate pouring of the water into the filling neck without a great portion of the same being wasted in order to avoid the spilling of the water upon the radiator shell or vehicle hood, which is now one of the difficulties generally experienced in the filling of radiators.

A further and important object is to provide a radiator cap that not only includes the above advantages, but one that will be ornamental and attractive in appearance.

With the foregoing and other objects in view as the nature of the invention is better understood, the same complies with the novel form, combination and arrangement of parts hereinafter more fully described, shown in the accompanying drawings, and claimed.

In the drawing, wherein like reference characters indicate corresponding parts throughout the several views:

Figure 1 is a front elevation of my improved radiator cap associated with the filling neck of a vehicle radiator which is fragmentarily shown.

Figure 2 is a top plan view thereof.

Figure 3 is also a top plan view disclosing the cap in an open condition for facilitating the filling of the radiator, and

Figure 4 is a view partly in elevation and partly in cross section of the cap as associated with the neck, said cap being shown in this view also in an open condition.

Now having particular reference to the drawing, there is fragmentarily shown at 5 a motor vehicle radiator that is provided with the usual filling neck 6 that is externally threaded at its upper end at 7.

My invention embodies the provision of a cap 8 of circular configuration that has the usual internally threaded flange for threaded engagement with the threaded end of the neck 6, as more clearly shown in Figure 4.

Formed upon the top side of said cap is a relatively oval-shaped housing 9 of relatively slight depth, the opposite ends of

which preferably extend beyond diametrically opposite points of the cap, as per Figures 1, 2 and 3. For ornamental purposes, the ends of this housing are provided with knobs or balls 10, which also afford a means in the application or removal of the entire cap with respect to the filling neck 6.

Disposed within said housing 9 and being of a shape similar to the shape of the housing is a funnel 11 formed of telescopic sections, as per Figure 4, which, when the same are collapsed, will fit snugly within the housing 9. The innermost one of these telescopic sections is in fixed relation to the cap 8 which is provided with a liquid entrance opening 12 in the center of said innermost section, Figures 3 and 4.

Hingedly secured, as at 13, to the upper telescopic section of the funnel at the rear edge thereof and intermediate its ends is a 75 cover plate 14 for the funnel receiving housing 9, which is obviously of the same contour as the housing, as shown in Figure 2.

A suitable latch means 15 is provided between said cover plate 14 and housing 9 80 in the front side thereof, for obviously maintaining the cover in closed relation with respect to the housing and for also preventing movement of the funnel sections within the housing when the same is closed.

From the foregoing description, it will be obvious that by releasing the latch means 15, the cover 14 may be forced upwardly which, by its association with the funnel sections, will also draw the funnel sections 90 into an extended position, as per Figure 4, for affording a guiding means for the water, through the opening 12 in the cap 8 and consequently into the radiator through the neck 6.

If desired, the housing cap 14 may be equipped with a conventional form of motor meter 16, and as a means for supporting the cover and motor meter in the position shown in Figures 3 and 4, when the cap is in open position, the housing 9 at the rear side thereof and intermediate its ends, is formed with a short vertical lug 17 upon which the adjacent edge of the cover plate 14 will rest. The lug 17 is slightly offset as is shown more clearly in Figure 4 to permit the adjacent portion of the cap to be disposed against the inner face of the lug when the cap rests on the housing in its closed position.

The meter meter 16 which provides a 110

weight for the cover 14 will cooperate with the cover and the lug in holding the collapsible funnel in its extended position.

From the foregoing description, when considered in conjunction with the accompanying drawing, the operation and advantages of a radiator cap of this character will be at once apparent, and even though I have disclosed what I believe to be the most novel embodiment of my idea, it is nevertheless to be understood that departures may be had without affecting the spirit and scope of the appended claim.

What is claimed is:

15 In a closure for radiator filling necks comprising a cap adapted for association with the filling neck, said cap having an opening in its top, a housing formed on the cap

around said opening, an offset lug extending vertically from the rear intermediate portion of the housing, a collapsible funnel including a series of telescopic sections which are adapted for normal disposition within the housing around said opening, a cover for the housing, said cover being hingedly associated adjacent the rear edge of the intermediate portion thereof to the uppermost section of the collapsible funnel, the rear intermediate portion of the cover being adapted to rest on the upper edge of said lug when swung to an open position, and a weight carried by the cover and co-operating therewith for holding the collapsible funnel in its extended position.

In testimony whereof I affix my signature.
CLAUDE WEYANDT.
